UNITED STATES PATENT OFFICE.

JOHN F. ALLEN, OF MARTINSDALE, MONTANA TERRITORY.

CASTRATING-INSTRUMENT.

SPECIFICATION forming part of Letters Patent No. 329,691, dated November 3, 1885.

Application filed September 7, 1885. Serial No. 176,405. (No model.)

To all whom it may concern:

Be it known that I, JOHN F. ALLEN, of Martinsdale, in the county of Meagher, in the Territory of Montana, have invented certain new and useful Improvements in Castrators, known as the "Horseman's Favorite;" and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention has for its object to provide an improved and simplified construction of that class of veterinary surgical instruments known as "castrating-instruments;" and the features of novelty consist, essentially, in the details of construction and general arrangement of parts, all as will be hereinafter fully described, and specifically designated in the claim.

In the accompanying drawings, Figure 1 represents a side elevation of my improved device, and Fig. 2 a detail view of the same.

Similar letters of reference indicate like parts in both figures.

Referring to the drawings, A represents the lower or stationary member of the instrument, having an elongated handle at one end terminating in a loop, a, for the reception of the fingers of the operator, and provided at the opposite or front end with an upwardly-bent portion, b, having a vertical slot, c, through the same, as fully shown in Fig. 2.

B represents the upper or movable member of the instrument, provided at its rear end with a handle and loop corresponding in size

and shape to that of the lower member, A, and pivoted at its front lower end within a recessed lug, d, upon the said lower member, as fully shown in the drawings. To the front upper end of the movable member B is pivoted the rear end of a hook, C, the front hooked portion, e, of which works freely through the slot c in the bent portion of the member A through the medium of the movable handle B.

In the operation of my invention the hooked end e is inserted to catch the cord connecting the testicles by raising the handle or member B, and by lowering said handle or member the hook is drawn in through the slot c, thereby drawing out the testicle-cord previous to completing the operation of castration.

By means of my improvements the surgical operation is greatly facilitated and attended with less risk and trouble than by the use of the ordinary appliances for the same purpose.

Having thus described my invention, what I claim as new and useful, and desire to secure by Letters Patent, is—

The herein-described veterinary surgical instrument, consisting of the lower stationary member, A, provided with the elongated handle and loop at one end and with the slotted bent portion at the opposite end, and the upper movable member, B, pivoted to the lower member, A, and provided with the hook C, substantially as and for the purpose specified.

In testimony that I claim the foregoing as my own I affix my signature in presence of two witnesses.

JOHN F. ALLEN.
